UNITED STATES PATENT OFFICE.

JAMES L. DONNELLY, OF PHILADELPHIA, PENNSYLVANIA.

FARE AND TRANSFER TICKET.

1,114,344.

Specification of Letters Patent.

Patented Oct. 20, 1914.

Application filed September 26, 1911. Serial No. 651,416.

To all whom it may concern:

Be it known that I, JAMES L. DONNELLY, citizen of the United States, residing at Philadelphia, in the county of Philadelphia and State of Pennsylvania, have invented certain new and useful Improvements in Fare and Transfer Tickets, of which the following is a specification.

This invention relates to transfer ticket systems designed primarily for use by street railway companies, and the primary aim of the invention is to prevent peculation on the part of the railway employees and at the same time to enable passengers to secure a rebate.

It is customary for street railway companies to sell tickets at a reduced rate when a number of tickets are provided at a time, for example, at the rate of six for twenty-five cents when the regular single fare is five cents, but under this system a dishonest employee could substitute tickets for the cash fares collected by him, and in this manner deprive the railway company of the profits which would otherwise accrue to them through the collection of cash fares.

The present invention, therefore, aims to provide a transfer ticket system by which peculation on the part of employees may be prevented, and at the same time the passengers will receive a rebate, equivalent to the amount saved by them in purchasing the ordinary tickets in quantities.

A further aim of the invention is to prevent the abuse of transfer privileges, or more specifically speaking, to render it impossible for a passenger to give away a transfer obtained by him except at a loss to himself.

For a full understanding of the invention reference is to be had to the following description and accompanying drawing, in which:

Figure 1 is a plan view of the transfer ticket embodying the present invention, viewing one side thereof. Fig. 2 is a similar view of the opposite side. Fig. 3 is a plan view of an excess check used in connection with the ticket shown in Figs. 1 and 2.

Corresponding and like parts are referred to in the following description and indicated in all the views of the accompanying drawing by the same reference characters.

The invention contemplates, as before stated, the provision of a transfer ticket and an excess check, and of these two the transfer ticket is shown in Figs. 1 and 2 of the

drawing, and is indicated in general by the reference numeral 1, it being perforated as at 2 to form a coupon 3 which may be readily detached from the body of the ticket. Upon the body of the transfer ticket near the top thereof there are printed the words "Fractional-transfer ticket," as indicated by the numeral 4, and below these words the name of the company issuing the transfer tickets, as indicated at 5. Below the name of the company there is printed a statement substantially as follows: "This fractional ticket denotes the value of 5/6 of a cent. Five of these tickets will be accepted as one fare, provided the required number be presented with five cents, upon the receipt of which the conductor will furnish the holder with an excess check which in turn may be tendered as fare." This statement is followed by a facsimile signature of the president or other officer of the company, as indicated by the numeral 7. Below this signature there is printed a statement as follows:— "A punch mark above the red line denotes P. M. hour and below the red line, A. M. hour. Void one hour after time canceled," as at 8. Columns 9 above the words "Fractional transfer" ticket are divided by vertical lines 10 into spaces upon which are printed numerals indicating the days of any month, as indicated at 11. At the right of the words "Fractional transfer ticket" there is printed the number of the ticket, as at 12, and the months of the year are printed as at 13 in a vertical column at the extreme right of the ticket. The ticket is divided by printed lines at its lower edge, into a transversely extending series of spaces 14 in which are printed numerals 15 indicating the hours of any day, there being also printed upon the face of the ticket a line 16 in red or some other distinctive color and this line extends through the entire series of the hour indicating numerals 15.

Upon the corresponding face of the detachable coupon 3 there is printed at the top thereof, the name of the division issuing the transfer ticket, as for example "Baker street division," as at 17 in Fig. 1 of the drawing, and below the name 17 the words "Transfer coupon," as indicated at 18. The number of the ticket is printed as at 19 immediately below the words "Transfer coupon" and below the number there is printed upon the said face of the ticket a statement 20, substantially as follows: "This coupon denotes that the entire ticket is a transfer.

Void if detached. See other side." The year is printed as at 21 at the bottom of the coupon 3 directly opposite the left hand end of the series of $\frac{1}{2}$ hour indicating figures 15. 5 The words "Not transferable" and a statement of the points at which the transfer is valid, are printed upon the opposite side of the body of the ticket, as shown at 22 in Fig. 2 of the drawing, and upon this side 10 of the transfer coupon, may be printed any qualifying statements relating to the use of the transfer tickets.

The excess check employed in connection with the transfer ticket is shown in Fig. 3 15 of the drawing and has printed upon one face the words "Excess check," as indicated at 23. There is also printed upon this face of the excess check the name of the railway division and the company using the excess 20 checks and transfer tickets, as indicated at 24, and also a statement 25 substantially as follows:—"This excess check denotes the value of five cents and upon its presentation as fare, the conductor will furnish the holder 25 with one fractional ticket." This statement is followed by a facsimile signature of the president or other officer of the company. Supposing the regular cash fare to be five cents, the fractional transfer ticket and excess 30 check are used in the following manner. Should a passenger desire to ride at the rate of $4\frac{1}{6}$ cents (the actual fare) when the passenger takes advantage of the rebate offered by the railway company, he 35 pays the conductor five cents and the conductor will then furnish him with a fractional ticket, minus the transfer coupon. On the other hand if the passenger should desire 40 a transfer, he should so inform the conductor and upon receipt of five cents the conductor will furnish the passenger with a fractional transfer ticket, that is the fractional ticket with the transfer coupon attached. Before handing this entire ticket 45 to the passenger the conductor will punch thereon the month, date, and hour.

It will be understood that a passenger obtaining a transfer will not be allowed a rebate, nor could he use the fractional part or 50 body of his ticket as a rebate even if the transfer coupon should be detached, for the reason that the punch marks in the said fractional part of the transfer ticket would indicate that the same was issued as a transfer. As before stated, it is an aim of the 55 invention to obviate the use of transfer privileges accorded passengers, and this is accomplished by the use of the fractional transfer ticket, inasmuch as it would not 60 be likely that a passenger would pay for a transfer which he does not need and then give the transfer to some other person.

The purpose of the excess check is to

keep a record of the fractional tickets presented as fare, and this is done in the following manner: When a passenger tenders five of the fractional transfer tickets together with five cents in cash, the conductor will accept the five fractional transfer tickets as a full fare, and will at the same time give to the passenger one of the excess checks shown in Fig. 3. This check is acceptable as a full fare, and upon receipt thereof, from the passenger, at any subsequent time, the conductor will give the passenger a fractional transfer ticket either punched for use as a transfer or not punched and with the transfer coupon detached.

It will be understood that by employing the excess checks, the conductors are compelled to register the fractional tickets received from passengers, and peculation in this manner is prevented.

It will be observed that a conductor must return to the company five cents for each 85 fractional transfer ticket and excess check issued by him.

Having thus described the invention what is claimed as new is:—

1. In combination, a ticket having a detachable portion, the ticket having thereon data indicating that when the said portion is detached the ticket will have a rebate value and that when the ticket is issued with the said portion attached the ticket will constitute a transfer, and an excess check having thereon data indicating that it is acceptable as fare and has a value equal to the regular fare plus the rebate value of the first-mentioned ticket.

2. In combination, a ticket bearing data indicating that when issued without cancellation of a certain portion thereof the entire ticket will constitute a transfer and that when the ticket is issued with cancellation of 105 said portion the remainder of the ticket will have a rebate value, and an excess check having a value in excess of the regular fare to be paid, the rebate ticket having a value equal to the value of the excess check in 110 excess of the regular fare to be paid.

3. In combination, a rebate ticket having a value equal to a fraction of the regular cash fare and acceptable, in predetermined numbers as fare, and an excess check purchasable at the time of tendering a number of the rebate tickets, as fare, the said excess check having a value equal to the full cash fare.

In testimony whereof I affix my signature 120 in presence of two witnesses.

JAMES L. DONNELLY. [L.S.]

Correction in Letters Patent No. 1,114,344.

It is hereby certified that in Letters Patent No. 1,114,344, granted October 20, 1914, upon the application of James L. Donnelly, of Philadelphia, Pennsylvania, for an improvement in "Fare and Transfer Tickets," an error appears in the printed specification requiring correction as follows: Page 2, line 56, for the word "use" read *abuse*; and that the said Letters Patent should be read with this correction therein that the same may conform to the record of the case in the Patent Office.

Signed and sealed this 8th day of December, A. D., 1914.

[SEAL.]

J. T. NEWTON,

Acting Commissioner of Patents.
